ROCKER ARM

Alfred H. Haberstump, Detroit, Mich., assignor
to The Murray Corporation of America, De-
troit, Mich., a corporation of Delaware

Application March 31, 1939, Serial No. 265,309

7 Claims. (Cl. 74—519)

The present invention relates to fabricated operating arms and is an improvement on the structure disclosed in the co-pending application of Alfred H. Haberstump, Serial No. 210,844, filed 5 May 31, 1938.

One of the primary objects of the present invention is to provide an improved rocker arm structure which is economical to manufacture.

Another object of the invention is to provide 10 an improved, stamped, sheet metal rocker arm formed of a single metal stamping, thereby providing a simplified and economical structure.

Another object of the invention is to provide 15 an improved simplified rocker arm of generally box section, having great strength and rigidity.

Another object of the invention is to provide an improved rocker arm for an automotive engine having a central bearing, an arcuate operating surface at the extension of one arm and a thread- 20 ed portion at the end of the opposite arm for association with operating elements.

Other objects of the invention will become apparent from the following specification, the drawing relating thereto, and from the claims herein- 25 after set forth.

In the drawing, in which like numerals are used to designate like parts in the several views throughout:

Figure 1 is a cross-sectional view through a 30 portion of an automotive engine illustrating a rocker arm according to the present invention associated therewith;

Fig. 2 is an enlarged elevational view of the rocker arm illustrated in Fig. 1;

Fig. 3 is a plan view of the rocker arm illustrated in Fig. 2;

Fig. 4 is a cross-sectional view taken substantially along the line 4—4 of Fig. 2;

Fig. 5 is a cross-sectional view taken substantially along the line 5—5 of Fig. 2; and,

Fig. 6 is a cross-sectional view taken along the line 6—6 of Fig. 2.

The structure of the present invention is directed to operating arms, such as rocker arms, bell cranks, and the like, and in the embodiment illustrated a rocker arm is employed in automotive engines for the purpose of operating the valves from the cam shaft.

Referring to the drawing, an internal combustion engine is generally indicated at 10, having a valve 11 of the usual poppet type. A tappet rod is indicated at 12 which is reciprocated in the usual way; and the tappet rod 12 is adapted to engage an adjustable set screw on one end of a 55 rocker arm generally indicated at 14, the other

terminal end of the rocker arm having an arcuate contact member for engagement with the valve stem, for translating a reciprocating movement of the tappet rod to the valve. The functions of the tappet rod, rocker arm and valve 5 are well known to those engaged in the internal combustion art and need not be described in detail here.

According to the present invention the rocker arm 14 is constructed of a thin sheet metal material stamped into the shape to be described thereby providing an economical construction for the rocker arm but at the same time providing a structure having the required strength and rigidity characteristics. The rocker arm 14 is 15 formed of a single strip of sheet metal material which is pre-stamped to the required shape and then folded upon itself and thereafter having the folded portions joined together to provide the finished article. 20

The single sheet of stamped metal is folded upon itself as indicated at 16, substantially midway between the ends thereof to provide superimposed layers 18 and 20. The upper layer 18 is provided with a longitudinally extending rib 22 25 terminating along its side edges in outwardly disposed flanges 24, the rib extending from a position adjacent the fold 16 to a position adjacent the opposite end of the arm and the flanges 24 extending substantially the full length of the arm. 30 The lower layer 20 is also formed with a complementary longitudinally extending rib 26, the side edges of which terminate in outwardly disposed flanges 28 complementary to the flanges 24.

The flanges 24 and 28 and the ribs 22 and 26 35 are shaped intermediate their ends to provide complementary portions which form a substantially circular transverse hub 30. A bearing bushing 32 may be disposed within the hub 30 so that the rocker arm 14 may be rockably mounted upon 40 a shaft 34 fixedly mounted on suitable standards on the engine.

The ribs 22 and 26 and the flanges 24 and 28 face each other, with portions of flanges 24 and 28 abutting each other so that a generally box 45 sectioned structure is provided which gives the rocker arm the strength and rigidity characteristics required in this type of article. The abutting portions of flanges 24 and 28 may be fixed together by spot welding, for example. 50

Portions of the flanges 24 and 28 are separated from each other adjacent the fold 16; and a contact member 36 is adapted to be disposed between the upper and lower layers 18 and 20, respectively, adjacent the fold 16. The lower layer 55

20 is provided with an opening 38 therethrough adjacent the fold 16; and the contact member 36 is formed with shoulder portions 40 which engage the facing edges of the spaced portions of flanges 24 and 28. The member 36 also has a portion which projects through opening 38 with the bottom surface thereof arcuate in shape as indicated at 42, and such arcuate surface is adapted to bear against the top of the valve 11. The projecting portion of member 36 is complementary in shape to the shape of opening 38, and it will thus be evident that through the engagement of shoulders 40 with the flanges 24 and 28 that the member 36 is rigidly fixed in position.

15 The ends of upper and lower layers 18 and 20, respectively, which form the terminal end of the arm 14 opposite to that of the folded end are each formed in the shape of generally round, complementary bosses 44 and 46, respectively,

20 which in turn are each formed with inwardly disposed flanges 48 and 49. The flanges 48 and 49 are generally circular in cross-section and are complementary to each other to provide an opening 50 therethrough which is threaded for

25 the reception of an adjustable set screw 52. The set screw 52 may be readily adjusted to adjustably set the rod 12.

From the above description it will be evident that the present invention provides a simplified structure which may be economically manufactured in that the portions 18 and 20 of the single strip of metal may be stamped to the shape described before these portions are folded at the mid-point between their ends. Such a stamping operation is a simple one; and after this operation the contact member 36 may be positioned so that the projecting portion extends through the opening 38 before the strip is folded. By thereafter folding the strip about mid-point 16 the flanges 24 and 28 engage shoulders 40, as described above, so that the member 36 is fixed in position. Also the portions of the flanges and ribs intermediate the ends of the arms when folded into the position shown in Fig. 2 are complementary to each other to form the hub; and the circular flange portions 48 and 49 are also complementary to each other to provide the opening 50. The flanges may then be fixed together by spot welding as mentioned above.

50 While a rocker arm for internal combustion engines has been specifically described, it is to be understood that the teachings of the present invention may be applied to the construction of other types of arms, such as bell cranks and the like. The arms of the present invention are rugged in construction but are light in weight because thin gauge metal material may be used.

Formal changes may be made in the specific embodiment of the invention described without departing from the spirit and substance of the invention, the scope of which is commensurate with the appended claims.

What is claimed is:

1. A stamped metal rocker arm comprising a metal strip folded upon itself to provide superimposed first and second layers, said first and second layers each having a longitudinally disposed rib terminating in outwardly disposed flanges, the ribs and flanges of the respective layers facing each other with portions of the facing flanges abutting each other and joined together to form a box section construction.

2. A stamped metal rocker arm comprising a metal strip folded upon itself to provide superimposed first and second layers, said first and

second layers each having a longitudinally disposed rib terminating in outwardly disposed flanges, the ribs and flanges of the respective layers facing each other with portions of the facing flanges abutting each other and joined together to form a box section structure, and other portions of the flanges intermediate the ends thereof being shaped to provide complementary portions forming a hub.

3. A stamped metal rocker arm comprising a metal strip folded upon itself to provide superimposed first and second layers, said first and second layers each having a longitudinally disposed rib terminating in outwardly disposed flanges, the ribs and flanges of the respective layers facing each other with portions of the facing flanges abutting each other and joined together to form a box section structure, other portions of the flanges intermediate the ends thereof being shaped to provide complementary portions forming a hub, the terminal end of one of said layers being provided with an opening, a contact member disposed within said opening and projecting downwardly therebelow, inwardly disposed circular flanges formed on both of said layers adjacent the other terminal end thereof forming a cylindrical opening.

4. A stamped metal rocker arm comprising a metal strip folded upon itself at substantially the midpoint between its terminal ends to provide superimposed first and second layers, said first and second layers each having a longitudinally disposed rib terminating in outwardly disposed flanges, the ribs and flanges of the respective layers facing each other with portions of the facing flanges abutting each other and joined together to form a box section construction, other portions of the flanges intermediate the ends thereof being shaped to provide complementary portions forming a hub, one of said layers adjacent said fold being provided with an opening, a contact member disposed between said first and second layers adjacent said fold having a portion projecting through said opening, and means forming a threaded opening through said arm adjacent the terminal end opposite to that of said fold.

5. A stamped metal rocker arm comprising a metal strip folded upon itself to provide superimposed first and second layers, said first and second layers each having a longitudinally disposed rib terminating in outwardly disposed flanges, the ribs and flanges of the respective layers facing each other, with portions of the facing flanges abutting each other and joined together to form a box section construction, other portions of the flanges intermediate the ends thereof being shaped to form complementary portions forming a transversely extending hub, one of said layers adjacent said fold being provided with an opening, the axis of said opening being at substantially right angles to the axis of said hub, said first and second layers having inwardly disposed flanges adjacent the terminal end of said arm opposite to that of said last named opening forming another opening with its axis substantially parallel to the axis of said first named opening.

6. A stamped metal rocker arm comprising a metal strip folded upon itself substantially midway between its ends to provide superimposed first and second layers, said first and second layers each having a longitudinally disposed rib terminating in outwardly disposed flanges, the ribs and flanges of the respective layers facing

each other with portions of the facing flanges abutting each other and joined together to form a box section construction, other portions of the flanges intermediate the ends thereof being shaped to provide complementary portions forming a hub, one of said layers adjacent said fold being provided with an opening, other portions of the flanges of said first and second layers adjacent said fold being separated from each other, a contact member disposed between said first and second layers adjacent said fold with shoulder portions disposed between and engaged by the separated flange portions, said member having another portion projecting through said opening, and means forming an opening through said first and second layers adjacent the terminal end of said arm opposite to that of said fold, said opening being threaded.

7. A stamped metal rocker arm comprising a metal strip folded upon itself substantially midway between its ends to provide superimposed first and second layers, said first and second

layers each having a longitudinally disposed rib terminating in outwardly disposed flanges, the ribs and flanges of the respective layers facing each other with portions of the facing flanges abutting each other and joined together to form a box section structure, other portions of the flanges intermediate the ends thereof being shaped to provide complementary portions forming a transversely extending hub, one of said layers adjacent said fold being provided with an opening, the axis of said opening being at substantially a right angle to the axis of said hub, a contact member disposed between said first and second layers adjacent said fold having a portion projecting through said opening, said first and second layers having inwardly disposed circular flanges adjacent the terminal end of said arm opposite to that of said fold, said flanges forming an opening with its axis substantially parallel to the axis of said first-named opening. 5 10 15 20
